UNITED STATES PATENT OFFICE.

JOHN CARLIN, OF CHICAGO, ILLINOIS.

AWNING.

1,183,950.

Specification of Letters Patent. Patented May 23, 1916.

Application filed October 8, 1914. Serial No. 865,620.

To all whom it may concern:

Be it known that I, JOHN CARLIN, a citizen of the United States, residing at Chicago, in the county of Cook and State of Illinois, have invented a certain new and useful Improvement in Awnings, of which the following is a specification.

My invention relates to awnings and the general object of the invention is to provide an awning which may be easily manipulated also one which will, when furled or raised, occupy but small space and cause the component parts to assume a position where they will not obstruct the view from the window.

Another general object is to provide an awning of such construction that all of the fixtures except the fabric of the awning itself may be permitted to remain in place during the winter without rendering the window unsightly or obstructing the view through the window.

Still another object is to provide a construction insuring against noise caused by rattling of parts in the wind.

Among the more specific objects of the invention which contribute to the accomplishment of the general object are; first, to provide an extension member located in position to be engaged and disengaged by the front rod of the awning when the latter is lowered and raised; second, to provide simple and efficient means for attaching the extension member to the window frame and at the same time tending to hold said extension member in vertical position where it will be up out of the way when not in active use; third, to provide certain details of construction which will be hereinafter more particularly described and claimed.

I accomplish my objects by the construction illustrated in the accompanying drawings, in which—

Figure 1 is a front view of a window equipped with my awning, the awning being shown to be in raised position. Fig. 2 is a side view of the parts shown in Fig. 1. Fig. 3 is similar to Fig. 2, but shows the awning lowered. Fig. 4 is a detail viewed from the front of the window showing the manner of attaching the extension element to the window casing. Fig. 5 is a vertical sectional view transverse to the cross bar of the extension member showing a preferred form of cord guide.

Similar numerals refer to similar parts throughout the several views.

In the forms selected to illustrate the invention, the awning, 1 is in the form of a strip of canvas or other suitable fabric, carried by a spring roller 2 mounted in brackets 3 secured to the casing 4. By preference the ordinary Hartshorn or spring shade roller is used. In order to stiffen the lower edge of the awning a front rod 5 is preferably secured thereto in the ordinary manner. The awning is manipulated by a pull cord 6 which is fastened to the lower end of the awning and preferably is connected directly to the front rod itself.

A horizontal roller 7 is journaled in brackets 8 fastened to the front of the window casing, and by preference this is located substantially on a level with the cross bars which form the lower bar of the upper sash and the upper bar of the lower sash. Below roller 7 is an extension element comprising the cross bar 9 and the side bars 10, 10.

The parts are so arranged that cross bar 9 will come about an inch below the bottom of the roller 7, approximately at the elevation of the sash bars just mentioned. The side bars 10 are arranged in front of the upright side members of the window casing 4. As a result of this arrangement, in which the side bars 10 are hidden from the view of a person within the window by the side members of the frame, and the roller 10 and cross bar 9 are hidden from the person by the above mentioned cross bars of the upper and lower sash, and the shade roller 2 is located at or near the top of the window frame, the parts of the awning, when out of use, are practically invisible from inside the window and hence do not in any way obstruct the view.

For this reason by simply removing the awning and its shade roller, the remaining parts may be left in position during the winter without causing any annoyance to the persons within the room; hence with an awning of my construction it becomes unnecessary to attach and detach the fixtures every spring and fall, as is common with most devices of this class.

At the lower end the extension bars 10 are secured by cotter pins 12 or otherwise to helical springs 13, the lower end of the bar passing down into the springs part way to obtain rigid connections. The lower end

of each spring is connected by a screw 14 or other means to the front of the window casing. In consequence the springs 12 tend to normally hold the extension bars 10 upright, 5 but permit said bars to be swung down when the awning is lowered. Thus the springs serve the dual function of hinges and means for holding the extension bars upright when not in use.

10 At the center of the cross bar 9 is a pulley 16 over which the cord 6 passes. An eye or keeper 17 acts as a guard to keep the cord in position upon the pulley and also acts as a stop against which the front rod 5 of the awning engages when the awning is being lowered. At the window sill 18 cord 6 passes under a pulley 19, which is preferably a catch pulley so that the cord may be retained in any desired position.

20 In operation, assuming the parts to be in the normal non-acting condition shown in Figs. 1 and 2, the operator lowers the awning by simply drawing in upon the pull cord 6. For the first half of its movement, that is, until the front rod 5 reaches the roller 7, it will pass straight down, close to the front of the window casing. If the operator continues to draw in on the cord the front rod 5 of the fabric strip will pass behind the 25 roller 7 and almost immediately thereafter will seat upon the stop 17 on the cross bar 9 and from that point on will draw said cross bar and the side bars 10 down with it until the parts have reached the limit of their 30 movement, as suggested in Fig. 3. If the operator now releases the cord the parts will move in the reverse direction, the springs 13 causing the bars 9 and 10 to rise in unison with the front rod 5 until they have resumed 35 their upright position adjacent to the front of the window casing. Thereafter, the awning will rise in the manner of an ordinary shade, the roller 7 holding the cord 6 close to the window frame and thus assisting in retaining the front rod 5 of the fabric strip 40 close to the front of said frame. Furthermore, by fastening the lower end of the pull cord at the catch pulley 19, said cord co-operating with the roller 7 will keep the rod 5 and side bars 10, 10 close to the window 45 frame.

From the foregoing it will be evident that with my awning the difficulties of manipulation are reduced to a minimum, it being 50 necessary merely to draw the cord 6 in or out, the springs in the roller 2 and at the bottom of the side bars 10, relieving the operator of the need of personally raising any weight. Another advantage in my construction is that the extension member, consisting 55 of the bars 9 and 10, simply swings up and down but never leaves its place in the sense of traveling upward with the awning. In other words, the extension member does not 60 travel vertically but simply swings from ver-

tical to horizontal position and vice versa. Consequently there is no weight to be raised and lowered by the operator, nor does the spring of the roller 2 have to raise the weight of the extension member. Said extension 70 member is capable of raising its own weight in rising to standing position and in fact as commonly constructed assists the spring roller 2 in raising the awning so long as the awning remains in engagement with said extension member. Another advantage of my construction lies in the fact that there are no loose parts. I have dispensed with all vertical guide rods and with sliding members, and the result is that there is nothing to 75 rattle in the wind either when the awning is lowered or when it is raised or when it is in intermediate position.

As a result of my preferred method of connecting the side bars 10 to the springs 13, 80 the tension of said springs may be readily adjusted. If a greater stiffness or tension is desired, all that is necessary is to withdraw the cotter pin 12 and lower the rod to a point farther down in the spring. In the 85 lower position a shorter portion of the spring is left for flexure and in consequence (within reasonable limits) the tension of said spring may be increased or decreased to any desired extent.

Having thus described my invention, what I claim as new and desire to secure by Letters Patent, is:—

1. In an awning, the combination of a shade roller, a fabric strip mounted thereon, 100 a cross roller in an intermediate position upon the window frame, a cross bar beneath said cross roller in position to be engaged by said strip when said strip is being lowered, side bars supporting said cross bar, means 105 attached to said side bars and attached to the window frame for normally holding said side bars upright, and means passing in engagement with said cross roller when the awning is raised for bringing said strip into 110 engagement with said cross bar as the strip descends.

2. In an awning, the combination of a shade roller supported at the top of the window frame, a fabric strip wound thereon, 115 a cord for raising and lowering said strip, a cross bar, an eye on said cross bar through which said cord passes, side bars supporting said cross bar, and means connecting said side bars with the window frame, said connecting means permitting said side bars to rotate in a vertical plane and preventing said side bars from moving bodily in a vertical direction.

3. In an awning, the combination of a 125 spring roller near the top of the window frame, a fabric strip mounted on said roller, a pull cord for operating said strip, a center roller behind which said cord passes, a cross bar near said roller, a guide for said cord 130

located on said cross bar, said guide also serving as a stop to engage the lower edge of the strip, and connecting means for articulately connecting said cross bar to the 5 window frame, said connecting means constraining said cross bar to travel approximately on the arc of a circle only.

4. In an awning, the combination of a spring roller near the top of the window 10 frame, a fabric strip mounted on said roller, a center roller, a cross bar beneath said center roller, side bars supporting said cross bar, springs fastened at one end to said side bars, and at the other end immovably fastened to

the window frame, an eye on said cross bar, 15 and a pull cord fastened to said strip and passing behind said center roller and through said eye to thereby cause the strip to actuate the cross bar when the strip descends, and rotate the cross bar and side bars 20 in opposition to the pressure of the springs.

In witness whereof, I have hereunto subscribed my name in the presence of two witnesses.

JOHN CARLIN.
